UNITED STATES PATENT OFFICE.

EMIL K. F. STREICHERT, OF DETROIT, MICHIGAN.

DESIGN FOR A RADIATOR COWL AND HOOD.

47,631.

Specification for Design.

Patented July 20, 1915.

Application filed June 7, 1915. Serial No. 32,754. Term of patent 7 years.

To all whom it may concern:

Be it known that I, EMIL K. F. STREICHERT, a citizen of the United States of America, residing at Detroit, in the county of Wayne and State of Michigan, have invented a new, original, and ornamental Design for a Radiator Cowl and Hood, of which the following is a specification, reference being had therein to the accompanying drawing, forming part thereof.

The figure is a perspective view of a radiator cowl and hood, showing my new design.

I claim:—

The ornamental design for a radiator cowl and hood, as shown.

EMIL K. F. STREICHERT.
